INFANT'S UNDERGARMENT

Rose M. De Luco, Jersey City, N. J.

Application September 17, 1938, Serial No. 230,375

2 Claims.

(Cl. 2—70)

This invention relates to infants' undergarments and has particular reference to a combination diaper and chest protector in which the diaper is so constructed and arranged as to comfortably and snugly fit about the waist and legs of the infant so as to cover and enclose the lower part of the torso, while providing a fullness in the front and rear portions adjacent the crotch to prevent chafing or rubbing.

The invention further comprehends a diaper in which the rear portion adjacent the top thereof extends forwardly at the sides thereof into overlapped relationship with the front portion of the diaper to seal the junctures therewith and with fastening means for connecting the overlapped portions together located forwardly thereof so as to render the rear of the garment smooth and free from anything which would be uncomfortable to the infant.

The invention also provides a diaper of elongated formation in plan comprising a front covering substantially rectangular end portion having a hemmed edge providing a tunnel for accommodating a tie string from which the opposite ends thereof protrude, a rear covering substantially truncated opposite end portion of greater width than the front covering portion and a crotch covering medial portion having recessed side edges and tie strings respectively at the juncture of the ends of the medial portion with the opposite end portions for retaining the recessed edges of the medial portion in intimate surrounding relation with the legs of the infant.

The invention also contemplates a diaper of two ply construction and in which one of the plies is folded over the other at one end to provide a tunneled hem and with draw strings protruding through the open ends thereof for connecting the opposite ends of the garment together in overlapped sealing relation.

The invention also comprehends a diaper provided with releasable means for engagement with the chest protector element to position and retain the same in chest covering relation and to assist in holding up the waist portion of the diaper.

With the foregoing and other objects in view, reference is now made to the following specification and the accompanying drawing in which there is illustrated a preferred embodiment of the invention.

In the drawing:

Fig. 1 is a perspective view of a diaper and chest protector constructed in accordance with the invention.

Fig. 2 is an enlarged view of the diaper removed from the chest protector and spread out in plan.

Fig. 3 is an enlarged fragmentary sectional view taken approximately on the line 3—3 of Fig. 2.

Fig. 4 is a similar view taken approximately on the line 4—4 of Fig. 2.

Referring to the drawing by characters of reference, A designates generally a diaper for covering and enclosing the lower part of the torso of an infant and B a chest protector which covers and protects the chest of the infant and serves to assist in holding up the waist portion of the diaper.

The diaper when laid out in plan is of elongated formation and comprises a substantially rectangular end portion 10 which overlies the front portion of the torso below the waist, an outwardly flared opposite end portion 11 which covers the rear lower portion of the torso and a crotch covering or medial portion 12 having inwardly curved or recessed opposite longitudinal side edges 13.

The front covering portion 10 of the diaper from its juncture with the medial portion 12 to its end edge 14 has its opposite longitudinal side edges 15 slightly recessed or concave, while the rear covering portion 11 from its juncture with the medial portion 12 to its point of greatest width is of substantially truncated formation and of greater width than the front covering portion 10 and has its opposite longitudinal side edges 16 slightly recessed or concave so that when the diaper is applied the flared side edges of the rear body covering portion 11 extend forwardly to overlie the hips of the child and into overlapping relationship with the front covering portion 10 to cover and seal the junctures therewith.

In order to fasten the diaper in position and to retain the recessed edges 13 of the medial portion 12 in intimate surrounding relationship with the legs of the infant, pairs of tie strings 17 and 18 are secured to the opposite longitudinal edges of the diaper at the juncture of the medial portion 12 with the opposite end portions 10 and 11. The opposite end portions 10 and 11 are respectively provided with pairs of tie strings 19 and 20 for tightening the diaper about the waist of the infant and for securing the flared side edges of the rear covering portion in overlapped relationship with the front covering portion 10.

The tie strings 19 are secured to the opposite side edges of the rear covering portion 11 at its point of greatest width, while the tie strings 20 consist of a length of tape arranged with its medial portion disposed and secured by stitching 55

21 in a transversely extending tunnel 22 formed in the front covering portion 10 and with its opposite tying ends protruding through the open ends thereof located intermediate the side edges 5 15 so that the front portion of the diaper may be ruffled to take up any slack to thereby avoid uncomfortable ruffling of the diaper in the back.

The rear body covering portion 11 is provided with inwardly converging side edge portions 23 10 which extend from the upper ends of the recessed edges 16 to the upper end edge 24, which end edge is parallel to the end edge 14 of the front covering section 10.

The diaper is composed of two plies 25 and 26 15 of soft fabric material which plies are intertuned at their opposite longitudinal side edges and along the upper edge of the rear covering portion and secured together between the plies by stitching 27, as illustrated in Figs. 2 and 4. The inner ply 25 20 at one end thereof is folded over upon itself and joined to the end of the outer ply 26 by transverse stitching 28 to provide the hemmed end 14 and which hemmed portion is provided with a spaced parallel line of stitching 29 and perpendicular stitching 30 extending from the line of stitching 28 to the terminals of the line of stitching 29 to define the tunnel 22, the stitching 28 being interrupted to provide tunnel outlets through which the extremities of the tape 20 protrude.

30 The chest protector B consists of a front or chest covering portion 31 having shoulder straps 32 extending from the lower opposite corners thereof which cross at the back of the infant and are slidably connected to the opposite upper corners of the front covering portion 31 by slide fastening elements 33 to take up the slack in the straps.

The front covering portion 10 of the diaper is provided with a pair of straps 34 having fastening elements 35 at the ends thereof adapted to engage 40 with complementary fastening elements 36 at the upper end of the rear body covering portion 11 for engagement with the shoulder straps 32 of the chest protector to position and retain the same in chest covering relation and to assist in holding up the upper portion of the diaper, while at the same time the straps 34 further function to retain the front and rear portions adjacent the top in overlapped relation.

What is claimed is:

1. In an infant's undergarment, the combination of a diaper and a chest protector, said diaper including a front body covering portion, a rear body covering portion and a crotch covering portion, said rear body portion extending forwardly into overlapped relationship with the front body covering portion adjacent the upper end thereof, interengageable fastening means on the rear and front body covering portions for connecting the same together in overlapped relation, said chest protector including a chest covering portion and shoulder straps connected to opposite diagonal corners thereof, and releasable fastening means on the front and rear body covering portions of the diaper for engagement with the said straps for positioning and retaining the chest protector in chest covering relation and for holding up the waist portion of the diaper. 5

2. In an infant's undergarment, a diaper of two 20 ply construction of elongated formation in plan comprising a substantially rectangular end portion adapted to cover the front portion of the body below the waist, an outwardly flared oppositely disposed end portion of greater width 25 throughout than said rectangular end portion adapted to cover the rear portion of the body below the waist, and a medial portion between said end portions having recessed side edges adapted to cover the crotch of the infant, tie 30 strings secured to the opposite edges of the diaper at the juncture of the medial portion with the opposite end portions for retaining the recessed edges of the medial portion in surrounding relation with the legs of the infant, said rectangular 35 end portion having a laterally extending tunnel opening at its ends through the outer ply and intermediate the side edges thereof, a draw string having terminals protruding through the ends of said tunnel and tie strings secured to the sides of 40 said outwardly flared opposite end portion adjacent the end thereof for engagement with the terminals of said draw string for connecting the opposite ends of the diaper together with the side edges of said outwardly flared opposite end portion arranged in overlapping relation with said rectangular end portion. 45
